UNITED STATES PATENT OFFICE.

LESLIE M. PARKER, OF EVANSTON, ILLINOIS.

FLEXIBLE-POST BINDER.

Application filed July 31, 1922. Serial No. 578,577.

To all whom it may concern:

Be it known that I, LESLIE M. PARKER, a citizen of the United States, residing at Evanston, in the county of Cook and State 5 of Illinois, have invented a certain new and useful Improvement in Flexible-Post Binders, of which the following is a specification.

This invention relates to post binders of the type wherein a flexible post is used. The 10 flexible post is preferably in the form of a link chain, although other forms of flexible posts may be used. In the form here illustrated gear teeth are cut directly into the flexible post and the driving mechanism 15 therefor takes direct hold upon the flexible post and it is not necessary to use sliding means to which the chain is attached. One 20 object of the invention is to provide a simple construction wherein direct hold is taken upon the flexible post itself and wherein that 25 part of the post which is under tension is pulled into the binder and that part of the post which is not under tension is pushed. Other objects will appear from time to time throughout the specification and claims.

My invention is illustrated more or less diagrammatically in the accompanying drawing, wherein:

Figure 1 is a horizontal cross section with 30 parts in elevation showing one of the backs of a binder;

Figure 2 is a vertical cross section taken on line 2—2 of Figure 1;

Figure 3 is a vertical cross section taken 35 on line 3—3 of Figure 1;

Figure 4 is a detail showing the post guiding member.

Like parts are designated by like characters throughout.

A is a hollow end piece within which the 40 tightening mechanism is located. It is provided with two end closing members A', A'', the member A'' being perforated to permit manipulation of the tightening mechanism.

B is one of the covers of the binder. It is 45 hinged to the member A as shown. C is the end section of the upper part of the binder and it is formed similarly to the member A, but in the present form it does not have

50 any tightening mechanism, although it might be made exactly the same as the lower member A and would then contain a duplicate of the tightening mechanism shown in that member. As shown it is merely pro-

55 vided with a pair of perforations C' through which one end of the flexible post extends.

Located within the member A is a pair of guiding and bearing members D. Each of these members is provided with a perforation D' adapted to serve as a bearing and is 60 also provided with a slot D², through which the flexible post passes. The top of the slot D² is provided with a rounded surface D³ about which the flexible post is bent and against which it bears. Extending inwardly 65 and in horizontal alignment with one side of the slot D² is a projecting member D⁴. This member serves as a guiding and retaining part to hold the flexible post in proper operative position. It is curved on its inner surface as shown to conform to the flexible post. 70

Supported in the bearings D' is a rotary operating shaft E shaped at one end as at E' to be engaged by a key whereby it may be rotated. Mounted upon the shaft E adjacent either end and opposite the member D⁴ of the member D is a worm E², these worms being formed opposite to each other.

Fastened at one end to the member C and extending downwardly through the perforations in the paper F within the binder is a pair of flexible posts G, G, preferably formed as link chains. These link chains have cut in one of their sides gear teeth G' adapted to mesh with the worms E² above 85 described, and to be moved by their rotation. The end link of each of the chains is left smooth and without any gear teeth as shown at G² in order to serve as a stop and to prevent the chain from being accidentally 90 turned out of engagement with the worms. The uppermost link of the chain G is formed as shown at H. This link is provided with the screw threaded bore H' and is adapted to receive a sectional post H². This section post is also provided with a screw threaded bore H³ and is adapted to receive a screw threaded member H⁴ which serves to prevent withdrawal of the chain through the upper cover C and thus acts as a tension 95 receiving member. In order to lengthen the chain the member H⁴ may be removed and other sectional members supplied, the member H⁴ always being screwed in the upper end of the top sectional post member. 100

I have shown a link chain of circular cross section, and while this is preferable the chain may be made of elliptical cross section or any rounded cross section. It might be generally angular with rounded corners, or it may be rectangular or triangular with rounded corners. Where in 110

the claims the expression "of rounded cross section" is used I do not wish to be limited to a chain of circular cross section. Any rounded cross section devoid of sharp corners is within the contemplation of my invention.

Where in the claims I have referred to the parts of which the flexible chain is made as being "substantially inflexible" I mean that the material of which they are made is not intended to be flexed or otherwise to yield in the operation of the binder. The parts are preferably made of steel or bronze. Each of these materials is to some extent flexible and also elastic but their elasticity and flexibility is not used in the operation of the binder. For that purpose the material may be considered substantially inflexible and inelastic, and the language of the claims is to be understood in this sense.

The use and operation of my invention are as follows:

Ordinarily no rigid sectional post members are necessary, a sufficient amount of expansion and contraction being provided by the movement of the chain into and out of the back of the binder. When the required number of sheets has been placed in the binder the shaft carrying the worms is rotated and since the worms are oppositely faced both of the chains will be drawn inward and the two backs of the binder drawn together so as to hold the papers in position. When it is desired to add more papers the shaft is rotated so as to loosen the binder and they are then tightened again when the paper has been inserted. The reverse of this process is carried out where paper is to be removed.

When a large quantity of paper is put into the binder it is sometimes desirable to increase its capacity in excess of the length of the chain normally forming part of the binder. This is done by removing the screw member at the top of the chain and by the addition of a suitable number of rigid sectional post members. However many of these members may be inserted the flexible post always remains at the bottom and this flexibility provides for the necessary adjustment for bringing the parts together to hold the paper.

Although I have shown an operative device, still it will be obvious that many changes in size, shape and relation of parts may be made without departing materially from the spirit of my invention.

In particular the chain might have gear teeth cut on the opposite side from the one shown in the drawing and the worms will be on that side instead of the side where they are now shown. Also the gear teeth might be cut to mesh with a pinion instead of a worm and the axis of rotation of such pinions would be substantially vertical with

the plane of the binder back. A further modification would include cutting gear teeth on the inner face of the chain, that is the face about which it bends and placing at the point of flexure of each chain a pinion about which it would bend and which would engage the gear teeth. By rotation of these pinions the chain would be brought in or moved out. Many other such changes of detail might be made, and I wish therefore that my showing be taken as in a sense diagrammatic, and I do not wish to be limited to the specific construction here shown.

I claim:

1. In a loose leaf binder a pair of covers and means for drawing them together, including a flexible member of generally circular cross section and means for gripping it intermediate its ends and for moving it in and out, said flexible member being formed of substantially inflexible material.

2. In a loose leaf binder, a pair of covers and means for drawing them together, comprising a flexible member of generally circular cross section and rotary means for gripping it intermediate its ends and for moving it in and out, said flexible member being formed of substantially inflexible material.

3. In a loose leaf binder, a pair of covers and means for drawing them together, comprising a plurality of flexible members of generally circular cross section and means for gripping them intermediate their ends adapted to draw them in and out, said flexible members being formed of substantially inflexible material.

4. In a loose leaf binder a pair of covers and means for drawing them together, said means including a flexible member of generally circular cross section, projections on said member and means for engaging said projections and for gripping said member intermediate its ends, said means adapted to draw said member in and out, said flexible members being formed of substantially inflexible material.

5. In a loose leaf binder a pair of covers and means for drawing them together including a flexible member of generally circular cross section, projections on said member and rotary means for engaging said projections and for gripping said member intermediate its ends and adapted by its rotation to draw said member in and out, said flexible members being formed of substantially inflexible material.

6. In a loose leaf binder, a pair of covers and means for drawing them together, said means comprising a plurality of flexible members of generally circular cross section, projections on said member and means for engaging said projections and for gripping said members intermediate their ends and

for simultaneously drawing them in or out, said flexible members being formed of substantially inflexible material.

7. In a loose leaf binder, a pair of covers and means for drawing them together, said means comprising a plurality of flexible members of generally circular cross section, projections on said members and rotary means for engaging said projections and for gripping said members intermediate their ends and for simultaneously drawing them in or out, said flexible members being formed of substantially inflexible material.

8. In a loose leaf binder, a pair of covers and means for drawing them together, said means including a flexible chain of rounded cross section, gear teeth cut in said chain and a gear mounted for rotation in engagement with said teeth and adapted by its rotation to move said chain in and out.

9. In a loose leaf binder, a pair of covers and means for drawing them together, said means comprising a plurality of flexible chains of rounded cross section, gear teeth cut in said chains and gears mounted for rotation in engagement with said teeth and adapted by their rotation to move said chains in and out, said gears mounted so as to move in unison.

10. In a loose leaf binder, a pair of covers and means for drawing them together, said means comprising a plurality of flexible chains of rounded cross section, gear teeth cut in said chains and gears mounted for rotation to move said chains in and out, said gears mounted upon a single shaft.

11. In a loose leaf binder, a pair of covers and means for drawing them together, said means including a flexible chain of rounded cross section, gear teeth cut in said chain and a gear mounted for rotation to move said chain in and out and a guide for said chain in opposition to said gear.

12. In a loose leaf binder, a pair of covers and means for drawing them together, said means including a link chain of rounded cross section, worm gear teeth cut in said chain and a worm gear, in engagement with said chain and means for rotating said worm to move said chain in and out.

13. In a loose leaf binder, a pair of covers and means for drawing them together, said means comprising a plurality of link chains of rounded cross section, worm gear teeth cut in each of said chains and a plurality of worm gears, one in engagement with each of said chains and means for rotating said worms to move said chains in and out, and guides for said chains in opposition to said worms.

14. In a loose leaf binder, a pair of covers and means for drawing them together, said means comprising a plurality of link chains of rounded cross section, worm gear teeth cut in each of said chains and a plurality

of worm gears, one in engagement with each of said chains and means for rotating said worms to move said chains in and out, said worms mounted so as to move simultaneously.

15. In a loose leaf binder, a pair of covers and means for drawing them together, said means comprising a plurality of link chains of rounded cross section, worm gear teeth cut in each of them and worm gears in engagement with each of them and a shaft upon which all of said gears are mounted, a guiding member for said chains and about which said chains are adapted to turn.

16. In a loose leaf binder a pair of covers, and means for drawing them together, said means including a flexible rack of generally rounded cross section made up of substantially inflexible parts, said rack attached to one of said covers, gears within the other cover adapted to engage said rack, means for rotating said gears, said gears adapted by their rotation to draw the rack into and move it out of said cover.

17. In a loose leaf binder, covers and means for drawing them together including an articulated rod, and means for gripping it intermediate its ends and for moving it in or out.

18. In a loose leaf binder, covers, means for drawing them together including a flexible member, a major part of whose circumference is curved, and means for gripping it intermediate its ends and for moving it in or out.

19. In a loose leaf binder, covers and means for drawing them together, a flexible member made up of substantially inflexible parts and means for gripping it intermediate its ends and moving it in or out, the flexible member and the gripping means being so shaped as to prevent accidental outward movement of the flexible member.

20. In a loose leaf binder, covers and means for drawing them together, a flexible member and rotary means for gripping it intermediate its ends and moving it in or out, the flexible member and the gripping means being so shaped as to prevent accidental outward movement of the flexible member.

21. In a loose leaf binder, covers and means for drawing them together, said means including a flexible chain, gear teeth cut in said chain, and a gear mounted for rotation in engagement with said teeth and adapted by its rotation to move said chain in or out, the shape of the gear teeth in said chain and the gear in engagement therewith being such as to prevent accidental outward movement of the chain.

Signed at Chicago county of Cook and State of Illinois, this 28th day of July 1922.

LESLIE M. PARKER.
